UNITED STATES PATENT OFFICE.

HARRY T. LOOMIS, OF NEW YORK, N. Y., ASSIGNOR TO FRANK & LAMBERT, INC., OF NEW YORK, N. Y., A CORPORATION OF NEW YORK.

DISPLAY-BOX.

1,030,903.

Specification of Letters Patent.

Patented July 2, 1912.

Application filed February 21, 1912. Serial No. 678,989.

To all whom it may concern:

Be it known that I, HARRY T. LOOMIS, a citizen of the United States, and residing at New York, in the county of New York and

5 State of New York, have invented certain new and useful Improvements in Display-Boxes, of which the following is a specification, such as will enable those skilled in the art to which it appertains to make and

10 use the same.

This invention relates to display boxes designed for use as receptacles for, and as means for displaying burial robes or garments, and the object thereof is to provide 15 an improved device of this class, particularly designed for displaying burial garments for men, but which may be used, if desired, for other purposes.

The invention which forms the subject 20 matter of this application is an improvement on that described and claimed in U. S. Letters Patent 656,723, granted to me, August 28, 1900, and said invention is fully disclosed in the following specification of 25 which the accompanying drawing forms a part, in which the separate parts of my improvement are designated by suitable reference characters in each of the views, and in which:—

30 Figure 1 is a plan view showing my improved display box with the cover removed;—Fig. 2 a partial section on the line 2—2 of Fig. 1, and;—Fig. 3 a sectional detail on the line 3—3 of Fig. 1.

35 In the practice of my invention I provide an oblong rectangular box *a* comprising a bottom part *a²*, a top part or cover *a³*, and the bottom part *a²* is provided within and around the top portion thereof, with reinforcing side strips *a⁴*, and corresponding reinforcing end strips *a⁵*.

40 For the purpose of this description the end *a⁶* of the box or the bottom part thereof will be called the head end, and the end *a⁷* the 45 foot end, and secured to the foot end of the bottom part of the box, and centrally thereof is a folding strip or member *b* preferably composed of card board or other fibrous material, and said strip is of a width approximately half that of the box, whereby 50 open spaces *c* are formed at each side of the bottom part of the box and range longitudinally thereof, and connected with the free end of the strip *b* is a transverse rod *d*, the 55 ends of which are provided with finger mem-

bers *d²* at right angles thereto, and adapted to enter sockets or recesses *d³* in the reinforcing side strips *a⁴* of the bottom part of the box.

The length of the strip *b* is preferably 60 less than half the length of the box, or the bottom part thereof, but the length of said strip may be increased or decreased within certain limits; and by means of the construction described the rod *d* is made 65 detachable, and the strip *b* may be folded backwardly, as indicated in dotted lines in Fig. 2, whenever desired. I have also shown within the bottom part of the box, a complete set of burial garments including, a 70 shirt front *e*, a vest *e²*, a coat *e³* and a pair of trousers *e⁴*, and the legs of the trousers are folded over one upon another, and in the use of my improved display box the legs 75 of the trousers are secured to the bottom of the strip *b* at two different points or as indicated at *e⁵* and *e⁶* in Fig. 2, and when the strip *b* is extended as shown in Fig. 2, the complete suit of garments will be clearly 80 shown, as will be readily understood, and as indicated in Fig. 2, and when the strip *b* is folded as shown in Fig. 1, the legs of the trousers, and the central bottom part of the skirt of the coat and a part of the sleeves of the coat will be covered by said strip, the 85 ends of the sleeves being partially exposed, and being provided with cuffs *g* which may be seen when the strip *b* is folded, as clearly shown in Fig. 1.

90 My improved display box may be made of any suitable material of any preferred size, and it will be understood that the cover *a³* forms a complete closure for the box for packing and shipping purposes, but said cover may be removed for display purposes 95 whenever necessary.

With my improvement the garments within the box and especially the trousers will be held in proper form at all times and when it is desired to use said garments no 100 pressing or ironing thereof will be necessary.

Having fully described my invention what I claim as new and desire to secure by Letters Patent, is:—

1. A display box of the class described comprising a bottom part, and a removable top part or cover, the bottom part being provided at one end thereof with a folding strip which is secured thereto, and which is 110

provided at its free end with a transverse rod adapted to be detachably connected with the opposite sides of said bottom part of the box.

- 5 2. A display box of the class described comprising a bottom part, and a removable top part or cover, the bottom part being provided at one end thereof with a folding strip which is secured thereto, and which is provided at its free end with a transverse rod adapted to be detachably connected with the opposite sides of said bottom part of the box, said folding strip being of less transverse dimensions than the box.
- 10 10 3. A display box of the class described comprising a bottom part and a removable top part or cover the bottom part being

provided at one end thereof with a folding strip which is secured thereto and which is of less length than the box, said folding strip being provided at its free end with a transverse rod the length of which is approximately the same as the width of the box, said rod being provided at its ends with angular projections adapted to enter 25 sockets or recesses in the sides of the box.

In testimony that I claim the foregoing as my invention I have signed my name in presence of the subscribing witnesses this 20th day of February 1912.

HARRY T. LOOMIS.
